(57) **CLAIM**

We claim the ornamental design for a handheld electronic communications device, as shown and described.

DESCRIPTION

The subject matter disclosed and claimed herein is related to the subject matter disclosed and claimed in U.S. patent application Ser. No. 29/279,068, filed on Apr. 19, 2007, the disclosure of which is incorporated herein by reference.

FIG. 1 is a rear perspective view of a handheld electronic communications device showing our new design.

FIG. 2 is a front perspective view thereof.

FIG. 3 is a left side view thereof.

FIG. 4 is a front view thereof.

FIG. 5 is a right side view thereof.

FIG. 6 is a rear view thereof.

FIG. 7 is a bottom view thereof; and,

FIG. 8 is a top view thereof.

The broken line showing of environmental structures is for illustrative purposes only and forms no part of the claimed design.
